JOHN KARMAZIN, OF DETROIT, MICHIGAN

HEADER CONSTRUCTION

Application filed March 31, 1927. Serial No. 179,786.

This invention relates to radiators for internal combustion engines, condensers and similar appliances, and more particularly to means for connecting the water passages of the radiator cooling section with the water supply tank, from which water is conducted to the engine or other device to be cooled.

In connection with the condensers of household refrigeration systems, and steam condensers in general, the cooling fluid may be under pressures in excess of one thousand pounds per square inch, and it becomes necessary to provide headers and especially joints between the headers and the radiator cooling section, so constructed as to resist the high pressure. It is further desirable that the use of solder be eliminated or reduced to a minimum, and that the water tubes open into the upper header in such a way that melted solder can not flow into and stop the tubes.

It is an object of the present invention to provide a radiator especially adapted for service under high pressure, and a method of assembling such a radiator. These and other desirable results are attained thru the instrumentalities, a representative embodiment of which will be hereinafter described, and is illustrated in the drawings, in which:

30 Figure 1 is a front elevation of a radiator embodying one form of the present invention.

Figure 2 is a fragmentary sectional elevation on the line 2—2 of Figure 1.

35 Figure 3 is a fragmentary front elevation of a slightly modified form of radiator.

Figure 4 is a fragmentary elevation, partly in section, on the lines 4—4 of Figure 3.

Figure 5 is a fragmentary sectional elevation on the line 5—5 of Figure 3.

Numerals 10 represents the upper header, and numeral 11 the lower header, both headers being of substantially circular cross section, although flattened on the side which receives the tubes of the cooling section. The cooling section may be of the general type described in my Patent No. 1,761,395, granted June 3, 1930. Said cooling section comprises a plurality of superposed fin and tube section elements 12, the conical tube sections 13 of

each element telescoping into the tubes of the next lower element.

The flattened upper surface 14 of the lower header member 11 is perforated to receive the tubes 16 of the lowermost fin and tube element 15, the entire length of the tubes passing into the perforations, and the fin resting in contact with the flattened exterior surface of the header, as clearly shown in Figure 2. Within the header and conforming thereto is placed a suitably shaped reinforcing plate 17, said plate being perforated to receive the parts of the tubes 16 which project thru the header wall. Within the reinforcing plate 17 is located another fin and tube section element, whose tubes 18 receive the projecting ends of the tubes 16, while the plate or fin 19 overlies the reinforcing plate 17.

It will be seen that the section of the header wall which is weakened by the openings for the water tubes is thus reinforced interiorly, and the part of the tube extending therethrough is double walled, ample strength as well as flexibility thus being insured.

A reinforcing means is provided for the upper header which may be constructed as follows:

The lower part of the header wall is flattened, as shown at 20, and a reinforcing plate 21 is interiorly fitted to the header wall, 80 covering the flat section 20, and adjacent parts of the curving wall 10. The top cooling section element 12 rests against the exterior face of the flattened header section and its tube sections 13 receive the tubes 22 of a 85 specially formed fin and tube element 23 which overlies the reinforcing plate 21 and conforms thereto. Additional tube sections 24 are placed within the tube sections 22, and project above the fin or plate 23 terminating 90 the water cooling tubes in a manner which prevents solder or other foreign material failing into the tubes and wholly or partially closing them.

A highly efficient radiator especially adapted for high pressure service is thus secured. The headers are generally of arcuate cross section, especially adapted to withstand pressure, and the section of the header wall which is perforated to receive the water tubes of the 100

cooling section is reinforced by the use of devices which are at the same time effective, simple in construction, readily assembled, and do not detract from the efficiency of the radiator cooling section.

5 The ends of the headers, which are of circular cross section, are closed by suitable heads 25 and 26 (Fig. 1), and suitable connecting fittings 27 and 28 are provided for 10 connecting the radiator into the system containing the fluid to be cooled.

15 The invention further contemplates the mounting of the radiator in a rigid frame, whereby stresses upon the joints of the cooling section, or between the cooling section and the headers are eliminated. Such stresses may be occasioned by rough handling of the radiator in transit, or in the operation of securing pipe connections to the headers.

20 To this end a construction is employed, one embodiment of which is illustrated in Figures 3 to 5. The headers are flattened on one side throughout their length, and are closed by means of plates comprising thickened sections 25 which are drilled and tapped to receive bolts. Such a header closing plate, having no outlet opening, is seen in elevation at the top of Figure 4, and its cross section is indicated in the adjacent part of Figure 3. The plate comprises a web 30 surrounded by a flange 31, which flange is enlarged at any convenient points, such as the junctions of the arcuate and flat sides of the head, to provide bosses 32 which are drilled and tapped to receive studs 35 or bolts 33. The lower header closing plate, shown at the bottom of Figure 4, comprises a similar web 30, border flange 31 and bosses 32, and in addition thereto a boss 34 which is drilled and tapped to receive an intake fitting 35. The opposite end of the lower header may be closed by a plate similar to the plate shown at the top of Figure 4, while the closure plate for the outlet end of the upper header may have the form shown in Figure 5. Owing 45 to the size of the outlet pipe 36 the web part of the plate is much reduced in area, and the bolt hole surrounding bosses are continuous with the outlet pipe surrounding boss.

50 Frame bars 37 and 38 pass from the ends of the upper header to the ends of the lower header and are secured to the respective header closing ends by the bolts 33. The frame bars have flat ends superposed upon the ends of the headers and fitting tightly against the latter. The frame bars and headers thus form a rigid structure adapted to resist the torsional stresses incident to screwing inlet and outlet fittings into the headers, and prevent any such stresses being transmitted to the radiator joints. The radiator cooling section is likewise protected by the frame from mechanical injury.

55 While one embodiment of the invention has been illustrated and described in detail this embodiment is to be understood as illustra-

tive rather than restrictive, the invention being susceptible of expression in many other forms, all falling within the scope of the appended claims.

What is claimed is:

70 1. A high pressure radiator comprising a header of substantially circular cross section, a cooling section comprising a plurality of water conduits, a part of the wall of the header having perforations adapted to register with the water conduits of the cooling section, a reinforcing plate within the header conforming to the header wall, having perforations registering with the perforations in the header, and devices passing through said perforations adapted to communicate with and engage the water conduits of the cooling section. 75

80 2. A high pressure radiator comprising headers having arcuate walls, a cooling section comprising a plurality of conduits extending between the headers, the headers having flattened wall sections which are perforated in alignment with said conduits, a reinforcing plate within each header extending over the flattened wall and adjacent parts of the arcuate wall, said reinforcing plates having perforations registering with the perforations in the header walls, and members having tube sections, adapted to engage and hold the water tubes of the cooling section, superposed on the reinforcing plates. 85

90 3. A high pressure radiator comprising a cooling section and a header provided with an interior reinforcing plate, the wall of the header and said reinforcing plate having registering perforations therein, and an element superposed on said reinforcing plate comprising tube sections adapted to receive the tubes 95 of the radiator cooling section. 100

105 4. A high pressure radiator comprising a cooling section and a header provided with a reinforcing plate, the header wall and reinforcing plate having registering perforations therein, and an element superposed on the reinforcing plate comprising a plurality of tube sections adapted to extend thru the reinforcing plate and the header wall, and to be received in the ends of the conduits of the cooling section. 110

115 5. A high pressure radiator having a cooling section comprising a plurality of superposed fin and tube elements, the tubes of said elements telescoping together to form continuous conduits, a header provided with perforations adapted to receive the tube sections of the lowermost fin and tube element, the fin resting upon the header wall, a perforated reinforcing plate within the header adapted to receive the part of the tube sections passing thru the header wall, and a fin and tube element superposed on said reinforcing plate and telescoping over the ends of the tube sections projecting thru the reinforcing plate. 120

125 6. A high pressure radiator having a cool-

ing section comprising a plurality of superposed fin and tube elements, a header having a wall section adapted to conform to the uppermost of said elements and provided with perforations in alignment with said tubes, a reinforcing plate within the header having perforations registering with the perforations in the header, a fin and tube member superposed on the reinforcing plate, the tubes of said member passing thru the reinforcing plate and the header wall and telescoping into the tubes of said cooling section, and tubular elements within said header telescoping into the tubes of said member, but extending above said member.

7. A radiator comprising upper and lower tubular headers, hollow cooling elements extending between and connecting said headers, ends for closing the opposite extremities 20 of the headers, each of said ends comprising a web, a peripheral flange and a plurality of perforated bosses, and an inlet connection for the radiator and an outlet connection therefore, one end of one header having a boss to receive one connection, and one end of the other header having a boss to receive the other connection.

8. A radiator comprising a pair of tubular headers, cooling elements extending between 30 and connecting said headers, ends for closing the extremities of the headers, frame bars having flat ends secured against the ends of the headers, and inlet and outlet connections for the radiator communicating therewith 35 through the ends of the frame bars.

9. A radiator comprising an upper header, a lower header, a cooling section intermediate said headers comprised of superimposed integral fin and tube type elements communicating with each of said headers and frame 40 bars extending from the ends of the upper header to the ends of the lower header and means to attach inlet and outlet connections to said headers without stressing said cooling elements.

10. A radiator comprising an upper header, a lower header and a cooling section intermediate said headers, closing means for the ends of said headers, frame bars extending 50 from the ends of the lower header to the ends of the upper header, the ends of the bars being flat and fitting against the headers, means for securing said frame bars to said header closing means, and inlet and outlet 55 connections in said header closing means.

11. A radiator comprising a rigid frame consisting of a header, both ends of said header being open, frame bars secured to said header, the ends of said bars being flat 60 and fitting against said headers to close said open ends, and a plurality of fluid conduits extending from said header, said fluid conduits being formed from superimposed integral fin and tube type elements, and fluid connecting means in the end of one of said

bars whereby the radiator may be connected in a fluid system without stressing the fin and tube type elements.

12. A high pressure radiator comprising a rigid frame consisting of a plurality of headers, said headers being spaced one from the other, frame bar means secured between said headers, and a cooling section extending between said headers, said section being formed from super-imposed integral fin and tube 70 type elements forming tubular fluid conduits, one of said headers having socket means to engage the tapered end of one of said tubular conduits and the other header having tapered flange means to engage the opposite end of 75 said tubular conduit, and fluid connecting means in the headers whereby the radiator may be connected in a fluid system without stressing the fin and tube type elements.

In testimony whereof I have affixed my 80 signature to this specification.

JOHN KARMAZIN.
